VIAL NECKING MACHINE

Robert H. Koenig, Vineland, N. J., assignor to
 Kimble Glass Company, Vineland, N. J., a cor-
 poration of Illinois

Application December 22, 1938, Serial No. 247,282

8 Claims. (Cl. 49—25)

The present invention relates to a machine for shaping the necks of vials, and more particularly to die mechanism for forming a thread on the neck of a vial. More specifically, the invention pertains to a novel form of rotatable die designed to cooperate with a plug which is insertable in the neck of the vial and which is expanded after insertion therein.

It is one of the objects of the present invention to provide a threading die, together with means for rotating the die and a lost motion or floating connection between the die and the means for effecting rotation thereof.

It is a further object of the invention to provide a novel form of plug consisting of two parts movable with respect to each other and adapted to be inserted in the neck of the vial being shaped to force the plastic glass into the thread forming contour of the die.

20 It is still a further object of the invention to provide means for expanding the plug in timed relation to the thread forming operation, which means includes mechanism for stopping rotation of the die.

25 Other objects will be apparent from the following description of the machine taken in connection with the accompanying drawings, in which:

Fig. 1 is a top plan view of the necking mechanism;

30 Fig. 2 is a side view partly in section of the mechanism shown in Fig. 1;

Fig. 3 is a front view partly in section of the machine shown in Fig. 1;

Fig. 4 is a diagrammatic illustration of the supporting rollers;

Fig. 5 is an enlarged fragmentary sectional view of the die and expandible plug; and

Fig. 6 is a front view of the plug shown in Fig. 5.

40 In the drawings, it will be seen that the mechanism is mounted on a tray 10, this tray being reciprocably slidable on the main part of the machine (not shown) and adapted to advance the plug and die toward a glass blank and withdraw them from the blank after the threading operation. Journaled in the main part of the machine forwardly of the tray 10 in brackets 11 secured to the frame of the machine are rollers or discs 12, some of which are adapted to support a glass blank 13 in axial alignment with a die 14 and expandible plug 15 and others of which are positioned laterally of the die to support the blanks over burners for preliminary heating thereof. A disc 16 is journaled with its axis positioned above the axes of discs 12 but skewed with

respect to the axes of rollers 12 to urge the blank 13 toward a stop plate 17 to position the blank accurately with respect to the die and plug.

Plug 15 consists of two arms 18, 18' pivoted on pins 19, their free ends having arcuate shaping portions 21, as indicated in Fig. 5. Pins 19 are secured to blocks 22, 22' adjustable laterally with respect to each other to permit the position of the pivots to be changed. This arrangement is necessary in order that the plug may be expanded 10 a predetermined distance depending on the internal diameter of the neck desired. The free ends of the arms 18, 18' are normally urged toward each other by springs 23, 23'.

Fixed to tray 10 is a support block 24 on 15 which a die holder 25 is slidably and adjustably supported. Rotatably journaled on the die holder is a die frame 26 having ball bearings 27 interposed between the frame and the die holder. The die frame consists of a cup-shaped bearing portion 28 having diametrically opposite webs 29 connecting the bearing portion of the holder with a ring 30. The die proper is indicated at 31 and consists of a circular plate having a threaded bore 32 designed to form threads on the vial 25 when the neck portion thereof is engaged by the die. This die is connected to the die frame by means of pins 33. One end of each of the pins 33 is headed at 34 and adjacent its other end a cotter pin 35 is inserted therein. Spring 36 surrounds each of the pins 33 and is interposed between the headed end of the pin and ring 30 to urge the die toward the holder, but permits the die to move axially relative to the holder. Interposed between ring 30 and the die is a flanged bearing ring 37. It is to be noted that rings 30 and 31 are provided with openings 38, 39 each larger in diameter than pin 33. On the other hand, openings 41 in the die have diameters substantially the same as that of pin 33. Hence, it will be seen that the die has a limited lost motion or floating connection with the die holder so that its axis may be adjusted radially and circumferentially as well as axially with respect to the die frame. This permits the die to adjust 40 itself automatically during the threading operation.

Integrally formed with the die frame is a plurality of blades 42 best shown in Fig. 3. The faces of these blades are disposed at an obtuse angle 50 with respect to a tangent drawn to the periphery of the die holder. Positioned adjacent the die holder is a nozzle 43 adapted to direct air under pressure against the blades 42 to revolve the die holder. The nozzle is provided with a valve 44 55

to permit regulation of the flow of air from the nozzle so that the speed of rotation of the die holder may be controlled.

The means for expanding the plug consists of a cam 45 fixed to shaft 46. Also fixed to the shaft 46 is a cam operating arm 47. Pivotally mounted on the machine frame is a rocker arm 48 having a lateral extension 49 thereon. This extension in turn is provided with a yoke arm 52 having a yoke at the end thereof cooperating with the cam operating arm 47. Suitable cam means 53 adapted to rock arms 48 and 54 swing the cam operating arm 47 toward the axis of the plug, causing cam 45 to move arms 18 and 18' away from each other. In this manner the plug 15 is expanded. Continued advancement of yoke 52 causes the cam operating arm 47 to be swung past the axis of the plug until lug 55 on extension 49 is positioned in the path of blades 42. When lug 55 engages one of the blades, further rotation of the die holder and die is arrested.

Prior to the threading operation the vial is preliminarily shaped or necked by means of a tool 56 swingable toward and away from the glass blank 13. This tool is mounted on arm 57 which in turn is secured to bracket 58 pivoted at 59. The bracket is provided with an opening 61 in which is positioned a rocker arm 62 adapted to be rocked by cam means 63 to rock arms 62 and 64, hence bracket 58, and thus first advance and then withdraw tool 56 with respect to the glass blank.

The die frame is adjustable vertically and laterally, as well as longitudinally, with respect to the support block. Vertical adjustment is effected by means of a suitable threaded connection (not shown) between the die holder 25 and block 24. The die holder is normally retained in a retracted position by spring 65, the latter being secured at one end to pin 66 on the holder and at the other end to a pin 67 on collar 68 which is fast on rod 69. Rod 69 is secured to carriage 71. It will be seen that block 24 is provided with an extension 72 having an upstanding flange 73 thereon. Slidable on rod 69 is a threaded collar 74 having a nut 75 adjustable along the length thereof against which spring 76 abuts. The other end of spring 76 bears against flange 73. To adjust carriage 71 and holder 25 laterally of block 24, there is provided a threaded rod 77 connected to the carriage with which cooperate nuts 78 bearing against stop piece 79.

The means for reciprocating the pan 10 and block 24, together with the carriage, holder and die frame mounted thereon, include cam 81, rocker 82, and bell crank 83, one arm of which engages fork 84 on block 24. Forward movement of the block causes flange 73, through spring 76 and collar 74, to urge carriage 71 and the die axially of and toward the blank to be shaped.

The operation of the machine will be apparent from the foregoing description. The blank is first transferred by a conveyor (not shown) to the adjacent rollers 12, the peripheries of which, as will be seen from the drawings, overlap each other to support the blank. At this station, the end of the blank is preliminarily heated after which it is moved into substantially axial alignment with the plug and die. At the last-mentioned station the blank is supported by the adjacent rollers 12, the peripheries of which are also in overlapping relation. Rotation is imparted to the blank by means of the skew roller which, in addition to rotating the blank, urges it toward the stop plate to position the blank in proper relation to

the sizing tool 56. This latter tool reduces the end portion to form an unfinished neck on the blank.

It will be understood, of course, that at the finishing station a relatively intense flame is directed against the rotating blank to melt the end portion thereof until it is in a plastic condition. The supporting tray is then moved forwardly by rocking of the lever 83 until the blank is positioned within the rotating die. At this time the reduced neck on the blank is somewhat smaller in diameter than the internal diameter of the die, and it is for this reason that the split plug is expanded to force the glass into the threads of the die. In this manner threads are formed on the outer wall of the neck while the inner wall thereof is smoothed by the arcuate surfaces of the plug.

As stated hereinbefore, the rotation of the plug expanding cam is effected by the extension 49 having thereon the stop piece or lug 55 which, when moved sufficiently toward the axis of the plug, will be positioned in the path of the blades 42 to arrest rotation of the die. At this time, cam 81 and lever 83 return the die holder to its normal position, the die is withdrawn and, since the skew roller continues to rotate the blank during withdrawal of the die, the blank is unthreaded therefrom. It is to be noted that the die is so mounted on its supporting plug that it has a lost motion or floating relation with respect thereto to enable it automatically to adjust itself during the thread forming operation. In so adjusting itself the cooperating die and plug form a threaded neck having a uniform wall thickness. On the other hand, while the plug expands to form a predetermined internal diameter on the neck, it also has a tendency to position the floating die in axial alignment therewith to insure the uniform thickness of the wall referred to.

While a preferred form of the invention has been illustrated and described, it is to be understood that it is not to be limited to the details shown in the drawings, but may be modified without departing from the basic features thereof as defined in the appended claims.

What I claim as my invention is:

1. In a vial necking machine, a die having a threaded bore for forming threads on the vial neck exteriorly of the neck, an expansible plug adapted to be inserted into the mouth of the vial neck and adapted to shape the interior of the neck, means for rotating the die, means for expanding said plug radially outward with respect to said threaded bore, and means for actuating said expanding means, said actuating means being engageable with the die rotating means after the plug has been expanded to arrest rotation of the die.

2. In a vial necking machine, a die for forming threads on the vial neck exteriorly thereof, an expansible plug adapted to be inserted into the mouth of the vial neck, means for rotating and supporting a vial in axial alignment with said die, a supporting member for said die, means for reciprocating said member axially with respect to the vial, a yieldable connection between said member and said die, and means for expanding said plug.

3. In a vial necking machine, a die having a threaded bore for forming threads on the vial neck exteriorly of the neck, a plug having a surface for shaping the interior of the neck, a rotatable die frame, said die having a lost motion

connection with said frame, and means for rotating said frame and said die.

4. In a vial necking machine, a die having a threaded bore for forming threads on the vial neck exteriorly of the neck, a plug having a surface for shaping the interior of the neck, a rotatable die frame, a yieldable connection between said die and said frame, said connection permitting limited circumferential and radial movement of the die relative to said frame, and means for rotating said frame and said die.

5. In a vial necking machine, a die having a threaded bore for forming threads on the vial neck exteriorly of the neck, a plug having a surface for shaping the interior of the neck, a rotatable die frame, a yieldable connection between said die and said frame, said connection permitting limited axial movement of the die relative to said frame, and means for rotating said frame and said die.

6. In a vial necking machine, a die having a threaded bore for forming threads on the vial neck exteriorly of the neck, a plug having a surface for shaping the interior of the neck, a rotatable die frame, a yieldable connection between said die and said frame, said connection permitting limited axial, circumferential and radial movement of the die relative to said frame,

and means for rotating said frame and said die.

7. In a vial necking machine, a die having a threaded bore for forming threads on the vial neck exteriorly of the neck, an expandable plug comprising a pair of arms each pivoted at one end and having a shaping portion at its free end, means normally urging the free ends of the arms towards each other, cam means engaging the arms intermediate the free ends and the pivoted ends and adapted to move the free ends 10 radially outward with respect to said bore to expand said plug, and means for varying the distance between the pivoted ends of the arms.

8. In a vial necking machine, a die having a threaded bore for forming threads on the vial neck exteriorly of the neck, an expandable plug adapted to be inserted into the mouth of the vial neck and having a surface for shaping the interior of the neck, said plug comprising a pair of independently pivoted arms, a pair of plug supporting members movable relative to each other, each forming a fulcrum for one of the plug arms, means for positioning said supporting arms in predetermined spaced relation to each other, and means for expanding said plug to urge the neck 25 of the vial into the threaded die.

ROBERT H. KOENIG.
